(57) **CLAIM**

The ornamental design for a bluetooth sleep mask, as shown and described.

DESCRIPTION

FIG. 1 is a perspective view of a bluetooth sleep mask showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the bluetooth sleep mask, shown in a position of use; and,

FIG. 10 is another perspective view thereof, shown in a position of use.

The broken lines in the drawings depict portions of the bluetooth sleep mask that form no part of the claimed design.
